PORTABLE POST DRIVER

Ernest D. Hauk, 1315 E. 23rd St.,
Signal Hill, Calif. 90806

Filed Jan. 9, 1967, Ser. No. 5,356

Term of patent 14 years

(Cl. D54—14)

FIG. 1

FIGURES 4 and 5 are, respectively, side elevations showing opposite sides of the post driver; and

FIGURES 6 and 7 are, respectively, top and bottom plan views thereof.

I claim:

The ornamental design for a portable post driver, substantially as shown.
